CONVERTIBLE WAISTBAND FOR
TROUSERS

Robert D. Punsly, Los Angeles, Calif.

Application January 26, 1940, Serial No. 315,797

4 Claims. (Cl. 2—236)

The present invention relates to convertible waistbands for trousers, and has for its general object to provide a convertible trousers for men in which the trousers may be made to assume a high-waisted condition suitable for use with braces or suspenders, or alternatively converted into a low-waisted or hip-waisted garment in which a portion of the high-waist may be turned over externally of the garment to simulate a belt 5 and to impart to the garment also the suspension characteristics of a belt.

The vogue for the high-waisted trousers which has continued for some time shows every evidence of becoming permanent due partly to the fact 15 that such waists greatly enhance the appearance of the trousers upon the wearer. However this type of trousers as at present made is subject to the objection that at all times one is required to wear braces or suspenders to maintain these 20 trousers in a correct position upon the person so as to give a correct and pleasing appearance and to avoid the slouching down of the trousers with their consequent ill-looking effect.

I have also noted the fact that the use of a 25 belt with this type trouser is not successful. However my experience has shown that a great many wearers of high-waisted trousers prefer the comfort of a belt, which as a matter of fact often-times becomes a necessity, because of the desire 30 of men to remove coats and vests particularly at home or when arriving at the office. Moreover in order to fully relax braces or suspenders are an encumbrance.

It is therefore an important object of the present 35 invention to combine in a single garment the comfort of the hip-trouser and the style of the high-waist.

This inventive concept is achieved generally speaking by the use of a convertible waistband 40 which is foldable upon the garment either upwardly or downwardly to convert the garment either into a high-waisted trouser or into a trouser of the hip type.

A further object of the invention is to dispense 45 with the necessity for altering trousers for instance from a high-waisted garment to a hip garment which in the terms of the trade is to "lower the rise" and which with the best of tailors is a costly, complicated and in most cases unsuccessful alteration.

It is a further object of the invention to secure 50 the advantages of the improved trousers with only negligible additional manufacturing cost.

With the foregoing and other objects in view 55 the invention will be hereinafter more fully de-

scribed and particularly pointed out in the subjoined claims.

In the drawings in which like parts are denoted by the same reference characters throughout the several views, 5

Figure 1 is a perspective view of an improved trousers constructed in accordance with the present invention and shown in a position of use with braces or suspenders as a high-waisted garment.

Figure 2 is a similar view with the braces removed and the garment converted to the hip type. 10

Figure 3 is a fragmentary perspective view with parts broken away and parts shown in section of the waist and belt portion of the improved garment taken on an enlarged scale. 15

Figure 4 is a transverse section taken on the line 4—4 in Figure 3.

Figure 5 is a front elevation with parts broken away of the trousers in an initial formative stage, 20 and

Figure 6 is a view similar to Figure 4 but with the belt section outturned.

Referring more particularly to the drawings the improved trousers are designated generally at 25 10 and as having a waist portion represented generally at 11.

As will more clearly appear from Figures 1 and 3 the waist is of that conventional form popularly known today as the high-waist, this waist reaching up considerably above the hip line of the wearer. Such waist carries preferably at the usual external points the buttons 12 for the attachment of the braces or suspenders 13, which are indicated in Figure 1, and which will preferably be used when the garment is employed in its original high-waisted condition. 30 35

In accordance with the invention I provide upon the interior upper portion of the high-waist 11 what I term as a belt section 14. This belt section 14 may be of any suitable material, cut and shaped to any desired form. One form may take the same pattern as the garment 10. 40

The belt section 14 may be of any suitable depth and it may be in one piece with the high-waist 11 if desired and folded over upon the upper edge of the waist and turned upon the inside of the garment, being stitched in place if desired by one or more lines of stitching as hereinafter indicated. The usual curtain is also shown in Figure 50 3 at 16.

As shown in Figures 1, 4 and 6, the line 17 indicates the line of flexure on which the belt 14 and the upper section 18 of the high-waist are together folded over to give the condition of the 55

garment shown in Figure 2, wherein the belt section 14 is now outermost and exposed, the high-waist of the garment lowered appropriately, and the garment converted into that type known 5 as the hip garment.

In order to aid in this folding operation the waistband of the trousers is advantageously formed with a vent 19, which may be the usual vent at the rear of the trousers.

- 10 Referring more particularly to Figures 3, 4, 5 and 6, I have here illustrated the canvas stay which may be modified in construction to constitute two sections 20 and 21 stitched along the lines 22 and 23 to the face of the garment 10 and 15 then split along the line of cleavage 24. In other words the canvas stay is sewed into the garment along the lines 22 and 23 in a whole piece or integral band, and after the stitching, such canvas is cut along the line 24 in order to provide a line 20 of waist break on which the belt section 14 and the upper waist section 18 may be folded. This line of waist break 24 will also communicate to the external appearance of the garment a horizontal circular line of suppression 17 spaced below 25 the upper edge of the high-waisted trousers a suitable distance to add to the trim and neat looking appearance of the garment. This line of suppression 17 marks the dividing line between the upper foldable outer waist section 18 and the 30 lower non-folding waist section 11.

The belt section 14 may be secured at the front open end of the trousers in any suitable manner, as for instance shown in Figure 3, by the extension waistband 25 having the hook 26 thereon to 35 loop through the eye 27 on the outer overlapped part of the waistband. With this form, when the trousers is converted to the hip type shown in Figure 2, the extension waistband 25 will become an external part and will contribute to the trim 40 and neat appearance of the waistband and the garment as a whole.

As also seen in Figure 3 a hook 28 on the external part of the waistband may loop through an eye 29 on the overlapped inner part to secure the 45 trousers together at the fly which is a usual form of fastening.

As shown to advantage in Figures 4 and 6, the lower edge 14^a of the belt section, viewed in its internal position in the high-waisted garment, extends appreciably below the line 24 of the waist 50 break so that when the upper foldable section 18 of the high-waist is folded over on the line of waist break 24 upon the lower fixed waist section 11, what was heretofore the lower edge 14^a of 55 the internal belt section now becomes the upper edge of the external belt section in the hip garment. The line of fold 24 of waist break is now below this upper edge 14^a of the external belt section 14 whereby such upper edge 14^a extends up 60 above any internal part of the waist of the garment to the end that no internal part of the waist may be seen but all will be concealed and the upper projecting edge 14^a of the external belt section, as seen in Figure 6, will present an uninterrupted, neat and tidy appearance.

As seen in Figures 3, 4 and 6, the curtain 16 is secured at its upper portion to the internal face of the internal belt section 14 along the line of stitching 30 which is in alinement with the line 70 of waist break 24 and foldable thereon. The curtain 16 is also stitched to the lower stay section 21 and to the outer face of the garment 10 along the line of stitching 31 which is spaced vertically below the lower edge 14^a of the belt section 14 when in its internal position.

Then by a comparison of Figures 4 and 6 it will be understood that the upper sections 18, 21 and 14 conveniently and quickly fold over outwardly and downwardly upon a line passing substantially through the suppression 17, the line of waist break or cleavage 24 and the line of stitching 30. Inasmuch as the edge 14^a of the belt section 14 is free of any connection beyond the line of stitching 30, such edge 14^a will stand up independently when the sections are folded over as shown in Figures 2 and 6 and form an uninterrupted, continuous neat-appearing upper marginal edge portion of the garment where the garment and the shirt merge.

In executing this folding movement as just described, the curtain 16 folds between the lines of stitching 30 and 31. In effect the line of stitching 31 holds down the active area of the curtain 16 which is undergoing the actual bending through substantially 180°. Thus the line of stitching 31 holds the curtain 16 down well within the confines of the upwardly-projecting upper free edge portion 14^a of the external belt section 14 in the converted hip type of garment. This folded over portion of the curtain 16 between the lines of stitching 30 and 31 presents a smooth appearance and prevents any internal part of the waist from rising up and revealing itself above the upper edge 14^a.

In fact this folded portion or area of the curtain 16 will be slightly stretched or put under tension by the outward act of folding which will tend to keep all interior parts of the waist compacted down in a close and non-revealing condition. The curtain 16 preferably extends below the lower section 21 of the canvas stay. All of these parts are exaggerated in size and possibly out of their true proportions in Figures 4 and 6 for the purpose of clarity in demonstrating and explaining this internal construction and its mode of operation. An upper line of stitching 32 may if desired and for purposes of finish extend through the infolded upper portions of the belt section 14 and waist section 18 and the interposed upper canvas stay section 20.

It will be noted that the lines of stitching 22 and 23 pass only through the canvas stay and the face portion of the garment 10 as these stitches are run through these parts before the canvas stay is severed into the sections 20 and 21 so that the continuance of these stitches through any other parts would render the inside surface of the canvas stay inaccessible to the knife that may be employed to achieve this cleavage. The line of stitching 30 only passes through the belt section 14 and the curtain 16 as it is undesirable to attach the curtain at its upper portion to either the canvas stay or the outside material of the garment.

In fact it will be found that the only point of connection of the curtain 16 with the canvas stay or the face material 10 of the garment is at the point 31, thus leaving the curtain 16 perfect freedom above this point which facilitates the quick and smooth movement of the belt section to the outer and inner positions.

Moreover the alinement of the stitches 30 with the waist break 24 and line of suppression 17 acts to reinforce and strengthen the garment at such points by a minimum thickness, the stitches being relatively thin in a vertical sense, so that while fulfilling the function of adding reinforcement and strength along the line of flexure or folding, yet the diminished thickness of such

means as stitches avoid any tendency to interfere with the flexing or folding action and such stitches do not add undesirable bulk at this point of folding, particularly where many thicknesses of material are involved.

It is obvious that various changes and modifications may be made in the details of construction and design of the above specifically described embodiment of this invention without departing 10 from the spirit thereof, such changes and modifications being restricted only by the scope of the following claims.

What is claimed is:

1. A garment comprising a high waistband 15 composed of upper and lower parts, a belt section carried within the upper part, upper and lower stays in said waistband parts, stitching securing said stays in place, said stitching being disposed close to the adjacent edges of said 20 stays, said stays being separated and providing a fold line in the waistband between the stitching and substantially coincident with the line between the upper and lower stays to facilitate folding of said parts and provide a neat stiffened 25 waistband when the parts are folded and when not folded to form a line of suppression extending around the high waisted garment spaced below the upper edge thereof.

2. A garment comprising a high waistband 30 composed of a lower non-foldable part and an upper foldable part, a belt section integral with said waistband and carried within the foldable part and being of substantially the same vertical depth as said foldable part, co-extensive stays 35 in said waistband parts, a plurality of lines of stitching securing said stays in place, said lines of stitching being disposed close to the adjacent edges of the stays, said stays being separated and providing a fold line in the waistband between the lines of stitching and substantially coincident with the line between the foldable and non-foldable parts of the waistband to facilitate the folding of said parts and to provide a neat stiffened 40 waistband when the parts are folded and when not folded to form a line of suppression extending around the high waisted garment spaced below the upper edge thereof.

3. A man's trousers garment comprising a waistband having fixed and foldable sections, a canvas stay within and secured to said waist-

band, spaced lines of stitching securing said stay at its intermediate part to the outer face of the garment, said stay being separated and providing a fold line in the waistband between the lines of stitching, a belt section secured to the interior of the waistband opposite to the foldable section and turnable on the outside of the garment when the foldable section is folded downwardly along the line of fold upon the fixed section, the lower edge of the belt section viewed 10 in its inner position being free and extending vertically below the horizontal line of said fold line to adapt such lower edge of the belt section, when out-turned to project upwardly above any adjacent inner portions of the belt section to 15 form a neat and trim upper edge for the garment when connected into a hip garment, and a curtain stitched along its upper edge portion to the inside of the belt section along substantially the line of fold and also stitched to the outer face 20 of the garment below the lower edge of the belt section.

4. An improved garment comprising a garment face material including a high waistband formed from such material including foldable and non-foldable sections, a stay backing said high waistband, separated lines of stitching connecting the intermediate part of the stay with the face material, said stay between said lines of stitching being severed to produce a line of waistband fold 30 resulting in a line of suppression of the face material following around said waistband fold, said waistband fold forming a weakened line of flexure on which the foldable waistband section is folded down upon the non-foldable waistband 35 section, a belt section of a face material lying inwardly of the foldable section of the waistband and having an extension edge projecting into the non-foldable waistband section, a curtain within said stay and having a portion outwardly of said belt section, a line of stitching connecting said belt section and curtain in alignment with the line of suppression and waistband fold, said edge of the belt section extending beyond the last mentioned line of stitching and being free of the curtain and other parts, and a second line of stitching below the waistband fold and passing through the face material of the garment, the stay and the curtain.

ROBERT D. PUNSLY. 50
